UNITED STATES PATENT OFFICE.

ROBERT F. HALL, OF SCHENECTADY, NEW YORK.

SWING-HANGER LINK FOR RAILROAD TRUCKS.

Application filed October 6, 1923. Serial No. 666,991.

To all whom it may concern:

Be it known that I, ROBERT F. HALL, a citizen of the United States, and a resident of Schenectady, in the county of Schenectady and State of New York, have invented a certain new and useful Improvement in Swing-Hanger Links for Railroad Trucks, of which improvement the following is a specification.

10 My invention relates, generally, to trucks for railroad rolling stock, of the class or type in which lateral resistance devices are provided, which is set forth in Letters Patent of the United States No. 1,060,222, granted and issued to W. F. Woodard, under date of April 29, 1913, and in applications for Letters Patent of the United States, filed by me November 29, 1922, Serial No. 603,916, and August 31, 1923, Serial No. 20 660,371.

My present invention particularly relates to swing hanger links for trucks of the type above stated, of the class known as "three point suspension," and its object is to provide a swing hanger link, in the operation of which a rapid rate of increase of resistance to the lateral swing or displacement of the bolster, will be attained during the initial stage of the movement thereof, and, at a predetermined point, the rate of increase of resistance will be decreased, so that the final resistance, when the bolster is displaced laterally to the maximum extent, shall be limited to a degree sufficient to maintain the 35 stability of the truck.

The improvement claimed is hereinafter fully set forth.

In the accompanying drawings: Figure 1 is an end view, in elevation, of a two wheeled locomotive engine truck, illustrating an application of my invention; Fig. 2, a similar view, illustrating the application of three point suspension swing hanger links of prior construction; Fig. 3, a diagram, illustrating the variation of lateral resistance in the constructions of Figs. 1 and 2; Fig. 4, an end view, in elevation, of a swing hanger link, embodying my invention; Fig. 5, a side view of the same, in middle position; Fig. 6, a similar view, showing the lower hanger member displaced to the left, to the limit of its movement independently of the upper member; and, Fig. 7, a similar view, showing the hanger fur-

ther displaced to the left, by coincident 55 movement of both members from the position shown in Fig. 6.

My invention is herein exemplified as applied in a two wheeled locomotive truck of the swing or lateral motion type, in which, 60 as in present practice, a frame, 1, is suspended, through the intermediation of springs, 11, on the journal boxes, 4, of an axle, 5, on which the truck wheels, 5^a, are secured. A swing frame or bolster support, 6, extends from one to the other of the side members of the truck frame, to which it is fixed at its ends, as by being made integral with the truck frame. The weight carried by the truck is primarily applied thereto through a floating or swing bolster, 7, which is provided with a centre plate, 7^a, perforated for the passage of a centre pin. The bolster is supported, with the capacity of lateral movement, relatively to the frame, by 70 swing hanger links, hereinafter described.

In the practice of my invention, referring descriptively to the specific embodiment thereof which is herein exemplified, the bolster, 7, is supported, at each of its ends, 80 on the bolster support and truck frame, by a swing hanger link, comprising an upper member, 8, provided with recessed bearings, which, in the normal or middle position of the link, fit over and rest on two journal 85 pins, 8^a, 8^b, fixed in the bolster support, 6, and a lower member, 9, provided with similar bearings, which, in normal position of the link, fit over and rest on two journal pins, 9^a, 9^b, fixed in the upper member. Each 90 end of the bolster is articulated to the adjacent swing hanger link, by a coupling pin, 9^c, fixed in the lower member of the link.

In the operation of a truck, in which swing hanger links of the construction 95 above described are applied, assuming the bolster to be deflected towards the left, the lower members, 9, of the links, swing about the axes of the pins, 9^b, and the lower members rise out of contact with the pins, 9^a. 100 Under these conditions, the resultant of the vertical and horizontal forces is, in the position shown in Fig. 5, intermediate the bearing pins, 8^a and 8^b, and the upper members, 8, therefore rest on both these pins 105 as bearings. If the bolster is further displaced towards the left, the lower members, 9, continue their swinging movements about

the axes of the pins, 9^b, and the resultant of the vertical and horizontal forces changes its angle, and moves towards the right, until the pins, 8^b, 9^b, and 9^c, lie in the same straight line, with which the resultant coincides. In the initial stage of movement from the normal or middle position to that last described, the horizontal force resisting the lateral displacement of the bolster, 10 is measured by the vertical load multiplied by the tangent of the angle, *a*, Fig. 5, which angle increases until it becomes the angle, *b*, Fig. 6. Further movement of the bolster towards the left, beyond the position of the 15 swing hanger shown in Fig. 6, causes the upper member, 8, to rise from the pin, 8^a, and the members, 8 and 9, swing, coincidentally, about the axis of the pin, 8^b. The line of the resultant still passes through the 20 axes of the pins, 8^b, 9^b, and 9^c, and this condition obtains throughout the remainder of the lateral displacement. The lateral resistance, during this final stage, is measured by the vertical load multiplied by the 25 tangent of the angle shown as *b*, which increases with the displacement, as to *c*, in Fig. 7.

It will be understood that when the bolster is displaced towards the right, the 30 operation above described takes place, in the same order, but in reverse direction. The characteristic curves of the resistances are shown in Fig. 3, and the corresponding positions are indicated thereon. The line, 35 4^x, shows the characteristic resistance curve of the three point hanger, and the line, 5^x, 6^x, and 7^x, the curve for the swing hanger of my invention. The points, 5^x, 6^x and 7^x, on the latter line, correspond with the 40 positions of the swing hanger shown in Figs. 5, 6 and 7, respectively.

In the operation of the ordinary type of three point swing hanger, 12, shown in Fig. 2, it is journalled on one or the other of 45 two pins, 12^a, 12^b, dependent upon the direction of the lateral movement of the bolster, and the lateral resistance is measured by the vertical load multiplied by the tangent of the angle, *d*. The characteristic 50 curve of this swing hanger is shown in Fig. 3. Fig. 2 illustrates a commonly used type of two wheeled locomotive truck having three point hangers, with the bolster, 7, displaced to its limit of movement to the left. 55 The resultant of the vertical load and horizontal forces is indicated as passing through the contact point of the truck centre pin with its seat in the top of the bolster. This line is parallel with the median line, 12^x, of the hanger in its displaced position, and intersects a horizontal line across the tops of the 60 rails at a point well within the outer rail. If the conditions were such as to cause the resultant line to pass outside the middle of 65 the outer rail, the truck would be liable to

overturn, particularly if a spherical bearing is provided for the centre pin.

At the period of the introduction of the three point hanger, locomotives were relatively small, as compared with later designs, and, for a given radius of curve, less lateral deflection of the truck bolster was required than at the present time. As indicated in Fig. 3, the resistance of a three point hanger increases rapidly with the lateral deflection, as is desirable in the initial portion of the deflection, for the reason that it permits of the application of a relatively low initial resistance, which increases rapidly, and checks any considerable movement of the truck bolster on tangent track, and by reason of this action, there is less liability to cause the wear on the hubs and flanges of truck wheels, which results from a high initial resistance. On the other hand, it is the fact that a low initial resistance, with a low rate of increase, would render the locomotive unsteady on tangent track. This operative feature of the three point hanger, limits the total amount of lateral displacement for which it is suited, as the resistance soon increases to such a degree as to render the truck unstable, when its bolster is displaced to the maximum lateral limit. The suggested remedy is to increase the length of the swing hanger, relatively to the distance between the upper bearing points, thereby reducing both the initial and final resistances. This change, however, would decrease the rate of increase of resistance, with the swing of the hanger, which, combined with the lower initial resistance, would make the truck unsteady when at or near the central position.

The improved swing hanger of my invention attains the operative advantage of obtaining a rapid rate of increase of resistance, during the initial stage of bolster displacement, while decreasing the rate during the final stage, so that the maximum resistance is not sufficiently high to endanger the stability of the truck.

The leading and characteristic feature of my invention is a swing hanger link, comprising a plurality of coacting members, which are so related and connected as to be endowed with the capacity of both relatively independent and coincident movement, and my invention is not, therefore, limited to its application in the specific construction herein set forth, in which two members only are combined to form my improved link. A greater number of members, similarly related and connected, may be provided, without departure from the spirit and operative principle of my invention.

I claim as my invention and desire to secure by Letters Patent:

1. A swing hanger link for lateral motion railroad trucks, comprising a plurality

of connected members, the first thereof being provided with bearings for permitting its movement on a support, and the others being journalled, successively, on the first and one on another, whereby each has the capacity of movement, both independently of the first and coincidently therewith.

2. A swing hanger link for lateral motion railroad trucks, comprising an upper member, provided with bearings for permitting its movement on a support; and a lower member, journalled on the upper member, with the capacity of both relatively independent and coincident movement.

15 3. A swing hanger link for lateral motion railroad trucks, comprising an upper member, provided with two parallel bearings, through either or both of which it is adapted to rest on a support; and a lower member, journalled, by two bearings, on the upper member, and movable both independently thereof and coincidently therewith.

20 4. A swing hanger link for lateral motion railroad trucks, comprising an upper member, provided with two parallel bearings, through either or both of which it is adapted to rest on a support; two parallel journal pins, projecting laterally from said upper member; a lower member, having bearings adapted to rest on said journal pins and to 25 turn on either of them; and a coupling pin,

fixed on the lower member, adjacent to its free end.

5. In a railroad truck, the combination of a main frame; a bolster, adapted to traverse laterally relatively thereto; a swing frame, fixed to the main frame; and a plurality of swing hanger links, each comprising an upper member, suspended on the swing frame, and a lower member, suspended on the upper member and articulated to the bolster.

35 6. In a railroad truck, the combination of a main frame; a bolster, adapted to traverse laterally, relatively thereto; a swing frame, 40 fixed to the main frame; a plurality of pairs of parallel journal pins, fixed in the swing frame; a plurality of swing link upper members, suspended on said journal pins, and adapted to swing on either pin of a 45 pair; pairs of parallel journal pins, fixed in said upper members; and a plurality of swing link lower members, each suspended on the journal pins fixed in one of the upper members, with the capacity of swinging on 50 either pin of the pair, and articulated to the bolster.

ROBERT F. HALL.
